OPTICAL FILTER HOLDER

Sidney Phillips, Brooklyn, N. Y.

Application July 13, 1948, Serial No. 147,514

Term of patent 7 years

(Cl. D61—1)

To all whom it may concern:

Be it known that I, Sidney Phillips, a citizen of the United States, residing in Brooklyn, in the county of Kings and State of New York, have invented a new, original, and ornamental Design for an Optical Filter Holder, of which the following is a specification, reference being had to the accompanying drawing, forming part thereof.

The figure is the side perspective view of an optical filter holder in a partially open condition, showing my new design, the opposite side presenting substantially the same appearance as the side shown.

I claim:

The ornamental design for an optical filter holder, substantially as shown and described.

SIDNEY PHILLIPS.
